GEORGE WORSTENHOLM, OF NEWARK, NEW JERSEY.

Letters Patent No. 76,873, dated April 14, 1868.

IMPROVED BOLT AND RIVET-MACHINE.

The Schedule referred to in these Letters Patent and making part of the same.

TO ALL WHOM IT MAY CONCERN:

Be it known that I, GEORGE WORSTENHOLM, of Newark, in the county of Essex, and in the State of New Jersey, have invented a new and useful Improved Machine for Making Rivets; and I have assigned the Letters Patent, when granted, to Morris Straus, of 123 Market street, Newark, in the county of Essex, State of New Jersey. I do hereby declare that the following is a full, clear, and exact description thereof, which will enable those skilled in the art to make and use the same, reference being had to the accompanying drawing, forming part of this specification, in which drawing—

Figure 1 is a plan view of the improved machine.

Figure 2 is a vertical section, taken in the plane of the line $z z$, fig. 1, showing, among other things, the heading-die.

Figure 3 is a vertical section, taken in the plane of the line $y y$, fig. 1, showing, among other things, the head of the shears and the friction-shoes enclosed therein.

Similar letters indicate corresponding parts.

This invention relates to machinery for making rivets, nails, and similar-headed articles from rods or bars of iron, or other metal, or from wire.

The letter a designates the frame of the machine, at one end of which is mounted the main shaft, b , which gives motion, through bevel-gears $c c$, to a transverse shaft, d , which has, like shaft b , suitable bearings in the frame.

The outer end of shaft d has circumferential cam-grooves $e e$, by means of which the horizontal feed-levers $f f$ are vibrated, said cam-grooves being so timed as to operate the levers in alternation.

The said feed-levers extend in opposite directions from the shaft d , until their other ends, which have slots that are elongated in the direction of their length, come above feeding-slides $h h$, which are placed near the sides of the frame, as shown in fig. 1.

The said levers $f f$ are pivoted to the frame at about the middle of their length, and are vibrated during the rotation of the shaft d by the action of the cam-grooves $e e$, in which the ends of the levers are allowed to rest. The slides $h h$ slide on ways in the frame, parallel to shaft d . Each of them contains a wedge-block, g , arranged on ways formed on the said slides, between their ends, as shown in figs. 1 and 2, to which the slotted ends of the vibrating-levers $f f$ are connected, respectively, by means of pins rising from the said wedge-blocks, and going through the slots of the levers. The block g is called a wedge-block because the left-hand end, observing fig. 2, which end projects under the adjacent end of the feeding-slide h , is inclined or bevelled on its upper face, the purpose or object in giving that form to it being to raise the vertical clamping-pin k , which hangs down from the slide h , and thereby press the blank or rod i against the lower ends of the screw l , by means whereof the rod i , from which the rivet or nail is to be formed, is firmly clamped in readiness for the feed-movement. The blocks $g g$ are moved inwards by the levers $f f$, at the beginning of their movements, so as to cause the rods $i i$ to be firmly clamped, the continuation of their vibration causing the forward shoulders of the blocks $g g$ to come against the forward ends of the slides, and carry the latter also inwards the required distance for the proper length of the rivet or nail, the length of feed being regulated by set-screws $u u$, which go through the outer ends $h' h'$ of said slides, and come against the outer ends of the wedge-blocks, so as to regulate and limit the extent of movement allowed to them in the slides.

The rods or blanks $i i$ are supported in the tops of the slides $h h$, as seen in the drawing, being caused to pass between the clamping-pin k and the adjustable screw l , as shown in the sectional view, fig. 2.

The rod i is pushed by the feeding-device through a perforated stationary head, m , and beyond it, (see fig. 2, and the right-hand side of fig. 1,) so that its end reaches a little beyond the dies $n n'$; the latter of which, n' , is stationary, and the former movable. The opposing faces of these dies have semicircular horizontal grooves, which, when the dies come together, enclose that portion of the rod which is to form the shank of the rivet or nail, and give to it the required shape, the inner edge of the movable die being made to project so as, in con-

junction with the face of the perforated head *m*, to act as a shears, and to cut off the rod to the proper length for the shank of the nail. The portion so cut off remains clamped between the dies until the heading-die *q*, being forced against its projecting end, forms thereon a head to the rivet or nail. The die and shears *n* are operated from a cam on the shaft *d*, said cam being surrounded by the head *o* of the die and shears, and the cam being so timed as to drive the die and shears *n* forwards at the proper time. The cam of shaft *d* does not act against the whole interior surface of the head *o*, but only against a friction-shoe, *p*, whose back is rounded so as to slide in a socket in the head, forming a joint therewith, while the sole of the shoe is curved to suit the curvature of the cam.

This construction and arrangement allow the cam to act upon the head to move it to and fro with a very slight degree of friction, the shoe being so held in its joint as to be allowed to adapt itself to the varying shape or curve of the cam.

The heading-die *q* is formed in the end of a sliding head, *r*, which is jointed, at *s*, to a connecting-rod, *t*, whose opposite end embraces an eccentric, formed on the main shaft *b*, the eccentric being properly timed to force the die *q* forwards at the moment when the end of the rod *i* is presented for its action.

The machine is so constructed and arranged that the feeding-devices, the clamping and shearing-dies, and the heading-dies, are each in duplicate, the same being operated either from the shaft *b* or the shaft *d*; as, for instance, the heading-dies *q* are actuated directly from shaft *b*, the clamping and shearing-dies *n* directly from shaft *d*, and the vibrating feed-levers *f*, and through them the other feeding-devices, from the same shaft *d* also.

The motions are so timed that the clamping-dies and shears *n* are withdrawn from the face of the stationary dies *n'* so soon as the heads of the rivets are formed, and the completed rivets are allowed to drop to the ground.

What I claim as new, and desire to secure by Letters Patent, is—

The feeding-slides *h*, and wedge-blocks *g*, in combination with screw *l* and pin *k*, that presses the rod *i* upwards to hold it while being fed to the machine, substantially as shown.

This specification signed by me, this 5th day of October, 1867.

GEORGE WORSTENHOLM.
